COUNTERBALANCE CRANK FOR PUMPING UNITS

Walter C. Trout, Lufkin, Tex., assignor to Lufkin Foundry & Machine Company, Lufkin, Tex., a corporation.

Application July 12, 1934, Serial No. 734,753
Renewed January 29, 1937

1 Claim. (Cl. 74—591)

The invention relates to an improvement in counter-balanced cranks for oil well pumping units.

In the pumping of oil wells it is desirable to counter-balance the load on the reciprocating walking beam so that a minimum of power will be necessary and a smoothness of operation obtained. At the same time it is also desirable to release the counter-balanced weight from the crank arm or pumping mechanism so that the pumping unit may be used for removing the pump or tubing from the well, or in otherwise performing what is known as servicing operations.

15 One of the objects of the invention is to provide a combination crank and counter-balance arm wherein the counter-balance may be adjusted longitudinally of the crank arm and increased in size as desired in order to obtain the necessary counter-balancing action.

Another object of the invention is to provide a combination crank and counter-balanced weight made up as a single unit which may be adjusted as to length.

25 Another object of the invention is to provide a counter-balanced crank which is made up of a plurality of independent sections adapted to be clamped together to form the crank and counter-balance.

30 A still further object of the invention is to provide a counter-balance weight attachment for crank arms such that the weight portion may be readily detached from the crank portion.

It is also an object of the invention to provide 35 a counter-balanced weight attachment to the crank arm such that the counter-balance may be removed by being detached laterally from the crank arm.

Other and further objects of the invention will 40 be readily apparent when the following description is considered in connection with the accompanying drawings wherein:

Fig. 1 shows an elevation of the invention wherein the length of the crank may be changed 45 and positioning of the weights may be adjusted by adding suitable plates thereto.

Fig. 2 is a section taken on the line 2—2 of Fig. 1 and looking in the direction of the arrows.

Fig. 3 shows a modification of the invention 50 wherein the device is spaced from the end of the crank and fixed in the desired counter-balancing position while it encloses or is fixed firmly with respect to the crank arm.

Fig. 4 is an edge view of the Fig. 3 form of the 55 invention.

In the embodiment shown in Figs. 1 and 2 an elongated body 33 is adapted to be mounted upon a drive shaft and is provided with a plurality of crank pin openings 32, to permit the changing of the stroke of the counter-balance crank. 5 Slots or grooves 44 and 45 are formed on one side of the body 33 and adjacent its edges to receive connecting bolts 15 which pass through cover plate 46 and are provided with nuts 48.

The counter-weight in this modification is 10 made up of a plurality of parts, but includes the base 35 through which the connecting bolts 15 are arranged to pass. This base 35 extends beyond the body 33 at each side and is arranged to receive a plurality of plates 37 which are held in 15 position by means of the bolt and nuts 38. In order to adjust the counter-balance weight so that it will perform the proper balancing action, it is sometimes desirable to adjust the weight radially with respect to the crank. With this in 20 mind, a plurality of spacer blocks 39 are adjacent the end of the body or crank 33. These weights are each provided with a tongue 40 to engage with a suitable groove in the next weight so that they will all be clamped securely together. 25

In order that the base 35 may be built up to provide the necessary counter-balancing action, a plurality of plates 42 are arranged to seat on each of the ears 43 of the base 35.

In this Fig. 1 form of the invention it will be 30 particularly noted that the bolts 15 are arranged to pass into the slots or grooves 45 formed in one side of the body 33. The upper end of these rods pass through a cover plate 46 so that a uniform pressure may be exerted upon the end 35 of the body when the device is in operative position.

When it is desired to service the well or use the pumping unit power independently of the crank arm and walking beam it is usually desirable to 40 remove the counter-weight so that it will not interfere with the use of the crank arm. To accomplish this with the Fig. 1 form of the invention it is only necessary to loosen the nuts 48 on the ends of the through bolts 15, so that the 45 bolts may be moved laterally around to the right, as viewed in Fig. 2, and in this manner release the counter-weight entirely from the crank arm. The crank can then be rotated during the servicing operation at a higher rate of speed. 50

Figs. 3 and 4 show another modification of the invention, wherein the crank body is illustrated at 50 and is provided with the upper and lower caps 51 and 52 through which the bolts 15 are adapted to pass. These caps serve to hold the 55

bolts in position within the openings 52 and 53 formed in the sides of the crank somewhat similar to the openings or grooves 45 in the Fig. 1 form of the invention.

5 It will be noted that the caps have an interfitting boss and socket construction at 55 so that they will be properly centered and firmly held in position. The bolts 15 are modified somewhat in this form of the invention and are provided 10 with the shoulders 56 so that the cap 52 may be drawn tightly against the end of the crank by manipulation of the nuts 57.

15 The counter-weight is indicated generally at 60 and includes the base 61 and the plates 62, as well as the counter-weight head 63. These 20 parts are interfitting as at 64 and are arranged to be fixed on the rods 15 by means of the adjustable nuts 66 and 67. It will be apparent that these nuts 66 and 67 may be adjusted along the bolts so that the base, plates, and head of the counter-weight may be adjusted longitudinally of the crank arm to obtain the desired 25 counter-balancing action. To secure the adjustment of these parts with respect to the arm, a locking bolt 69 has been provided so that the nuts thereon may be set tightly against the weight head 63 and the cap 52. This serves to lock the parts in position and prevent any vibration which would tend to destroy the device. When it is desired to remove the counter-weight the nuts 57 30 will be loosened and the cap 51 raised sufficiently to disengage the boss and socket construction so that the bolts may be moved over laterally to completely remove the counter-weight.

An eye 70 has been shown on the cap 51 so that when the nuts 57 are loosened and the bolts 15 moved away from crank 50 a suitable hoist may be connected to the bolts, caps and weight, so that the device may be handled conveniently, 5 or moved to a position such that it will not interfere with the rotation of the crank 50 during the servicing of the well.

While two specific forms of the invention have 10 been disclosed, it is to be understood that the invention is not confined thereto, but that changes may be made in the construction and combination of parts without departing from the spirit of the invention.

15 What is claimed is:

A counterbalance crank arm for well pumping units comprising an arm body for attachment to the crankshaft of the unit, wrist pin openings therein, a groove the length of said body disposed at each edge of the body, a rod 20 disposed in each groove, a cap plate across one end of said body through which said rods pass, a plurality of spacer bars at the other end of said body, and on said rods, a base weight in which the ends of said rods are anchored and 25 which is positioned below said spacer bars, and nuts on said rods to bear against said cap plate to hold the parts assembled but adapted for release whereby said rods may be moved laterally out of said grooves to remove the weight from 30 said crank body.

WALTER C. TROUT.
